W. MANNING

Des. 160,103

DESK

Filed Jan. 29, 1949

Inventor,

*William Manning
by T. B. Slioz attorney*

UNITED STATES PATENT OFFICE

160,103

DESK

William Manning, Chicago, Ill.

Application January 29, 1949, Serial No. 578

Term of patent 3½ years

(Cl. D33—7)

To all whom it may concern:

Be it known that I, William Manning, a citizen of Germany, residing in the city of Chicago, county of Cook, and State of Illinois, have invented a new, original, and ornamental Design for a Desk, of which the following is the specification, reference being had to the accompanying drawing, forming a part thereof.

The figure is a perspective view of the desk embodying the design.

I claim:

The ornamental design for a desk, substantially as shown.

WILLIAM MANNING.
